WINDMILL FOR ADVERTISING SIGNS OR THE LIKE

Paul M. Lewis, Box 224, Englewood, Colo.

Filed July 13, 1962, Ser. No. 70,913

Term of patent 14 years

(Cl. D1—12)

FIG. 4

FIG. 1 is a side elevational view of a windmill for advertising signs or the like showing my new design;
 FIG. 2 is a top plan view thereof;
 FIG. 3 is a front elevational view thereof; and
 FIG. 4 is a rear elevational view thereof.
 The blades are shaded to indicate color contrast.
 I claim:
 The ornamental design for a windmill for advertising signs or the like, shown and described.
